FREEZING DEVICE POWER UNIT

Arthur J. Frei, Dayton, Ohio, assignor to General Motors Corporation, Detroit, Mich., a corporation of Delaware

Application May 23, 1958, Serial No. 737,250

6 Claims. (Cl. 62—135)

This invention relates to a freezing device in which an ice-operated power unit or motor moves walls of a grid in a tray of a freezing device.

For several reasons freezing devices of the tray and grid type wherein an ice motor moves walls of the grid have not become generally popular. Firstly, the manufacturer of such devices has experienced difficulty in making an ice motor therefor small and compact yet capable of ample movement of elements of the motor for tilting grid walls in a tray of the freezing device a sufficient distance to insure release of all ice blocks from their compartments. Secondly, there has been confusion in the use of such devices that has led to annoyance on the part of the user thereof resulting in complaints. For example if the ice motor in a freezing device is incapable of tilting all of the plurality of grid walls in a tray of the device a sufficient distance ice blocks in the compartments between the grid walls not tilted a prescribed distance adhere to the walls and remain locked in the grid when the grid is removed from the tray. This defeats the objective of the device and necessitates ice blocks remaining in the removed grid, if they are desired for immediate use, to be melted or forcibly ejected therefrom. Also the ice motor of such a freezing device may tilt one grid wall therein to cause ice blocks adjacent thereto to elevate the grid and other ice blocks still bonded to its walls relative to the tray before the motor and its cooperative elements has acted on or tilted all other of the grid walls. In other words there may be somewhat of a delay between the time the one grid wall is tilted, to elevate the grid and ice blocks relative to the tray, and subsequent tilting of all other of the grid walls. Under this condition a user of a refrigerator in which the freezing device is located desiring to harvest ice blocks will, upon viewing the grid elevated in the tray, assume that all ice blocks are loosened from the grid and remove the freezing device from the refrigerator and the grid from the tray to find that only the few ice blocks are loosened and available for use. This is an embarrassing situation and the freezing device, being without a manually operated lever or the like for ejecting ice blocks from walls of the removed grid, requires the user to replace the grid and ice blocks bonded thereto into the tray and to reposition the freezing device in the refrigerator for further or continued chilling of the ice motor to render it effective to tilt all the walls of the grid. This invention is therefore directed to overcoming defects in former freezing devices employing a so-called "slow acting" ice motor and specifically to eliminating confusion in the use of such devices.

An object of the invention is to provide an improved ice-operated power motor or unit for the grid of a tray and grid type freezing device.

Another object of this invention is to provide an ice-operated power motor for a grid of a freezing device which will insure a prescribed shifting movement of ele-

2

ments of the motor away from one another so as to move or tilt all walls of the grid substantially instantaneously in response to a predetermined low temperature.

A further object of this invention is to provide means in an ice-operated power motor for a grid of a freezing device that will increase expansion of a freezable liquid in the motor in a certain direction for multiplying the shifting or travel of elements of the motor at a predetermined temperature to insure a positive and quick movement of the walls of the grid disposed in a tray of the freezing device.

In carrying out the foregoing objects it is a still further and more specific object of this invention to provide in an ice motor of a tray and grid type freezing device a means for constricting the expansion of a freezable liquid in the motor and of converting the constriction thereof into a confined increased linear expansion whereby to multiply and obtain a quicker movement of elements of the motor.

Further objects and advantages of the present invention will be apparent from the following description, reference being had to the accompanying drawings, wherein a preferred form of the present invention is clearly shown.

In the drawings:

Figure 1 is a vertical sectional view of a tray and grid type freezing device equipped with an ice-operated motor constructed according to this invention;

Figure 2 is an enlarged longitudinal sectional view of the ice-operated motor shown in Figure 1 with elements thereof in their normal position before expansion of liquid in the motor takes place; and

Figure 3 is a view similar to Figure 2 showing elements of the motor moved after liquid confined therein has been sufficiently frozen or expanded to shift an actuating plunger to its outermost position.

This invention is particularly applicable to a tray and grid type freezing device of the character disclosed in the Harvey D. Geyer Patent 2,576,591 dated November 27, 1951, and assigned to the assignee of the present application. Since the herein disclosed invention is directed to an improvement in the ice-operated motor unit portion of a freezing device as shown in the Geyer patent and since the grid structure is fully illustrated and described in that patent, no detailed description of the construction and operation of the grid is necessary herein. Figure 1 of the drawing is substantially a duplicate of Figure 2 in the Geyer patent with the improved ice-operated motor unit substituted for that shown by Geyer.

In Figure 1 of the drawing the freezing device shown therein comprises briefly a container pan or tray 10 having a bottom and upwardly extending and outwardly diverging side and end walls. A grid structure 15 is removably disposed in tray 10 of the freezing device and includes partitions or partitioning walls dividing the interior of the tray into a plurality of compartments in which water placed in the device is to be frozen into separated ice blocks under a below freezing temperature produced by an evaporator of a refrigerating system associated with a household refrigerator cabinet. Grid structure 15 comprises a main longitudinal partition or wall 16, a series of spaced apart cross or transverse partitions or walls 17, each loosely anchored or mounted upon main wall 16, and an actuating bar 18 overlying partition 16 and mounted thereon. Walls or partitions 16 and 17 and bar 18 are interlocked together to provide a unitary removable structure in the manner described in the Geyer patent above referred to so that walls 17 are capable of a relative tilting movement with respect to wall 16. The central portion of actuating bar 18 is cut away to provide an elongated opening therein having such dimensions as to suitably receive and cradle an ice-operated motor unit,

generally represented by the reference numeral 20, on grid 15 which unit is constructed as will be hereinafter described and to which the present invention is directed.

Referring now to Figure 2 of the drawing, the ice motor 20 in Figure 1 includes two reaction elements adapted to be forced to move relative to one another. One of these elements is in the form of a one-piece tubular member 21 having integral ends 22 and 23 of different diameter with respect to one another. The smaller end 23 of element or member 21 has a bore 24 therein and the larger end 22 thereof is provided with an elongated cylindrical chamber 26 axially aligned with bore 24. Chamber 26 is divided into an enlarged portion and a choke portion provided by the inclined wall 27 which tapers from the enlarged chamber toward the bore 24. The chamber 26 is of a substantially larger diameter than the diameter of bore 24 and is directly opposite the bore to communicate therewith by way of tapered wall 27 which wall forms a choke portion in the motor 20 for a purpose to be hereinafter described. A plug 28 seals the outer end of chamber 26 and a pin or stud 29 passes through an opening in this plug and an opening in an upward projection 31 on longitudinal wall or partition 16 of grid 15 (see Figure 1). This locks the one end of element 21 of motor 20 to the grid wall 16. The other reaction element of motor 20 has a plunger or piston 33 formed thereon and slidably mounted within bore 24 of element 21. Plunger or piston 33 has its inner end disposed adjacent to the choke portion, wall 27, of element 21 and forms a closure for the inner end of chamber 26. The outer end 34 of plunger or element 33 may abut against a part of actuating bar 18 on grid 15 and is preferably suitably attached to ears 36 formed thereon by a pin or stud 37 (see Figure 1). In order to tie the actuating elements 21 and 33 of motor 20 together and permit relative movement thereof away from and toward one another a flexible resilient interlock seal means is provided therebetween. This interlocking seal may, as far as the present invention is concerned, be of any suitable or desirable construction and is herein shown as being a stretchable rubber-like sleeve 41 provided with spaced apart internal ribs 42 and 43. Rib 42 of sleeve 41 fits in a groove 46 cut in the small end portion 23 of element 21 while rib 43 fits in a groove 47 cut in a part 48 of the other reaction element intermediate its plunger 33 and its outer end 34. Metal collars 49 are roll or press fitted over end portions of the rubber-like sleeve 41 to lock ribs 42 and 43 in their respective grooves 46 and 47. Sleeve 41 is sufficiently flexible to permit considerable stretching thereof upon sliding movement of plunger 33 outwardly of bore 24 and is of such resiliency as to pull the reaction elements of motor 20 together after shifting of these elements away from one another.

Cylindrical chamber 26 forms or provides an expansion compartment or chamber for motor 20 which is filled with and contains a freezable expansion fluid of any suitable or desirable character or composition such as water or a mixture of water and alcohol prior to sealing or closing the end of chamber 26 by plug 28 to confine the fluid therein. The machined sliding fit of plunger 33 in bore 24 is such that none of the freezable liquid in chamber 26 is capable of leaking past the plunger but if some of the liquid should so leak sealing sleeve 41 prevents its escape from motor 20. Sleeve 41 normally holds the end of plunger 33 of the one reaction element of motor 20 immediately adjacent the gradually tapered choke portion, wall 27, of the other element 21 and movement of the plunger and consequently expansion of the liquid in chamber 26 are yieldably opposed. The reaction elements 21 and 33 of motor 20 are adapted to be moved relative to one another when the liquid within the sealed expansion chamber 26 expands preferably at a temperature below the temperature at which water freezes into ice blocks in the compartments of the freezing device. Movement of the reaction elements of motor 20 away from one an-

other is utilized to move or tilt inclined walls or partitions 17 of grid 15 relative to the partition 16 toward the vertical for breaking bonds between ice blocks frozen in the freezing device and walls of the tray and grid to automatically, in response to a predetermined temperature below that of the ice blocks, loosen ice blocks from their enlarged compartments and permit harvesting thereof. It is to be understood that the choked fluid expansion chamber of motor 20 could, without departing from the realm of this invention, if desired, be in the shape of a spheroid for constricting the expanding freezable liquid but such shaped chambers are difficult and expensive to provide.

Water is placed in tray 10 of the freezing device to such a level that motor 20 will normally lie adjacent to but out of contact with the water therein. The freezing device is then placed in or on a refrigerated shelf or support in a freezing chamber of a refrigerator so that heat is transferred through walls of the tray and grid to the refrigerated support. The limited metal-to-metal contact of motor 20 with grid 15 aids in preventing the water or water and alcohol freezable mixture confined in the unit or motor from freezing until after all ice blocks in the freezing device have been hard-frozen. After such hard-freezing of ice blocks the freezable mixture confined in chamber 26 of motor 20 gradually freezes and expands in volume at a predetermined temperature below the temperature at which the ice blocks are frozen. This expansion and increase in volume of the freezable liquid mixture in chamber 26 is constricted by the tapered wall 27 thereof and concentrated to expanding at a localized point in a linear direction against the end of element or plunger 33. The expanding freezable liquid will push plunger 33 outwardly of bore 24 of motor 20 with a force capable of overcoming very high resistance and at an increased speed and as the plunger moves outwardly of the bore it opens or exposes a part of the bore to communication with chamber 26. By constricting the expanding liquid and localizing its expansion as herein described the freezable liquid expands into the opened or exposed part of bore 24 and sliding movement of plunger or reaction element 33 is thereby greatly multiplied to insure a quick and complete movement of element 33 away from element 21 a prescribed increased distance at a predetermined temperature (see Figure 3). It is to be noted that stretching of rubber-like sleeve 41 to extend same as shown in Figure 3 of the drawing causes its wall to thin out or be reduced in thickness to place the sleeve under tension which tension is employed to move the elements 21 and 33 back toward one another into their normal position as shown in Figure 2 after motor 20 has been operated and after the freezable liquid has absorbed heat and has contracted within chamber 26. Since plug 28 of reaction element 21 is secured, as by pin or stud 29, to wall 16 and the end 34 of reaction element 33 is secured, as by pin or stud 36, to actuating bar 18 of grid 15 this bar 18 is forced to move with respect to the stationary portion or element 21 of motor or unit 20 as indicated in Figure 3 toward the left hand end of the freezing device as viewed in Figure 1 of the drawing relative to the longitudinal wall or partition 16 of the grid structure. In other words the elongation of ice motor 20, or movement of its reaction element 33 away from reaction element 21, causes a relative sliding movement between bar 18 and longitudinal grid wall 16. Sliding of bar 18 causes notches provided therein and fitting over an edge portion of each of the transverse walls or partitions 17 to engage and tilt these walls in succession one after the other for loosening ice blocks in compartments of the freezing device from both the tray 10 and grid 15 so that they may be readily harvested from the device as is fully illustrated and described in the Geyer patent hereinbefore identified. The increased or multiplied movement of plunger 33 within bore 24 obtained by choking, constricting and concentrating expansion of the freezable liquid in motor 20 as herein disclosed provides a rapid or substantially instantaneous shifting of

all walls of the grid structure 15 through a prescribed distance at a predetermined temperature even though walls 17 are moved in succession.

It should, from the foregoing, be apparent that I have made an improvement in ice-operated motor units for freezing devices which results in a quick movement of elements thereof throughout a desired or prescribed distance in response to a predetermined temperature. This result is accomplished in a novel manner by an ice motor having a choke portion in its freezable liquid chamber which constricts expansion of the liquid and increases the expanding thereof in a concentrated linear direction to cause the movement of a movable plunger or piston to be multiplied over that heretofore obtained in prior ice motors. Such is highly desirable and important in ice-operated motors used in conjunction with a grid structure of a freezing device of the type herein disclosed because the substantially instantaneous movement of all grid walls overcomes the confusion and objections as hereinbefore explained to former ice-operated motors. Also by my invention the multiplied movement of the motor piston renders the motor more adaptable to ice-operated types of ice block makers wherein the increased movement of the motor piston can be used to move or shift other elements in addition to grid walls for accomplishing various results. For example, the multiplied movement of an ice motor piston as obtained by the present invention provides a motor that is highly satisfactory for use in an ice making apparatus of the type disclosed in my co-pending application S.N. 737,249, filed May 23, 1958, in which the additional movement of the motor piston is utilized to rotate a grid member out of a tray member of a freezing device for discharging ice blocks loosened in the device therefrom.

While the form of embodiment of the invention as herein disclosed constitutes a preferred form, it is to be understood that other forms might be adopted, as may come within the scope of the claims which follow.

What is claimed is as follows:

1. An ice motor for a freezing device of the character including a tray and a grid therein having a plurality of relatively movable partitions dividing the interior of the tray into compartments in which water is to be frozen into separated ice blocks, said motor comprising reaction elements forced to move relative to one another at a predetermined temperature below the temperature at which water in the device freezes for reacting between partitions of the grid to move them, one of said reaction elements having a bore in an end thereof and a chamber opposite to and communicating with said bore, said chamber being substantially larger than the diameter of said bore and having a choke portion tapered toward same, a plunger on the other of said reaction elements slidably mounted in said bore, said plunger being beyond said chamber with its end normally disposed adjacent said choke portion thereof and closing the chamber, said chamber containing a freezable liquid, said freezable liquid expanding in said chamber at said predetermined temperature and being constricted by said chamber choke portion whereby expansion thereof against said plunger multiplies sliding of the plunger in said bore to shift said elements away from one another.

2. An ice motor for a freezing device of the character including a tray and a grid therein having a plurality of relatively movable partitions dividing the interior of the tray into compartments in which water is to be frozen into separated ice blocks, said motor comprising reaction elements forced to move a prescribed distance relative to one another at a predetermined temperature below the temperature at which water in the device freezes for reacting between partitions of the grid to move them, one of said reaction elements having a bore in an end thereof and a chamber opposite to and communicating with said bore, said chamber being substantially larger than the diameter of said bore and having a choke portion tapered

toward same, a plunger on the other of said reaction elements slidably mounted in said bore, said plunger being beyond said chamber with its end normally disposed adjacent said choke portion thereof and closing the chamber, said chamber containing a freezable liquid, said freezable liquid expanding in said chamber at said predetermined temperature against said plunger to slide same in said bore and to expose a part thereof to the chamber whereby said freezable liquid expands into said exposed part of the bore while being constricted by said chamber choke portion for multiplying the sliding movement of the plunger to shift said elements away from one another throughout said prescribed distance.

3. An ice motor for a freezing device of the character including a tray and a grid therein having a plurality of relatively movable partitions dividing the interior of the tray into compartments in which water is to be frozen into separated ice blocks, said motor comprising reaction elements forced to move relative to one another at a predetermined temperature below the temperature at which water in the device freezes for reacting between partitions of the grid to move them, one of said reaction elements having a bore in an end thereof and an aligned cylindrical chamber communicating with said bore, said chamber being divided into a first portion having a cross sectional area substantially larger than the diameter of said bore and a choke portion gradually tapered from said first portion thereof toward the bore, a plunger on the other of said reaction elements slidably mounted in said bore, said plunger being beyond said chamber with its end normally disposed adjacent said choke portion thereof and closing the chamber, said chamber containing a freezable liquid, said freezable liquid expanding in said chamber at said predetermined temperature and having its expansion constricted by said chamber choke portion whereby to increase lineal movement of the expanding freezable liquid against said plunger and multiply sliding of the plunger in said bore for shifting said elements away from one another.

4. An ice motor for a freezing device of the character including a tray and a grid therein having a plurality of relatively movable partitions dividing the interior of the tray into compartments in which water is to be frozen into separated ice blocks, said motor comprising reaction elements forced to move a prescribed distance relative to one another at a predetermined temperature below the temperature at which water in the device freezes for reacting between partitions of the grid to move them, one of said reaction elements having a bore in an end thereof and an aligned cylindrical chamber communicating with said bore, said chamber being divided into a first portion having a cross sectional area substantially larger than the diameter of said bore and a choke portion gradually tapered from said first portion thereof toward the bore, a plunger on the other of said reaction elements slidably mounted in said bore, said plunger being beyond said chamber with its end normally disposed adjacent said choke portion thereof and closing the chamber, said chamber containing a freezable liquid, said freezable liquid expanding in said chamber at said predetermined temperature against said plunger to slide same in said bore and to expose a part thereof to the chamber, and said choke portion of said chamber constricting expansion of said freezable liquid to increase lineal movement thereof whereby it expands into said exposed part of the bore and multiplies the sliding of the plunger to shift said elements away from one another throughout said prescribed distance.

5. An ice motor for a freezing device of the character including a tray and a grid therein having a plurality of relatively movable partitions dividing the interior of the tray into compartments in which water is to be frozen into separated ice blocks, said motor comprising reaction elements forced to move relative to one another at a predetermined temperature below the temperature at

which water in the device freezes for reacting between the partitions of the grid to move them, one of said reaction elements being in the form of a one-piece tubular member provided with integral ends of different diameter with respect to one another, said member having a bore in its smaller end, an enlarged aligned chamber in its larger end and a choke portion providing communication between the bore and said enlarged chamber, means for sealing one end of said chamber, a plunger on the other of said reaction elements mounted in said bore for sliding movement therein a prescribed distance, said plunger being wholly outside said chamber with its inner end disposed adjacent said choke portion of said element to close the other end of said chamber, said chamber containing a freezable liquid, and said freezable liquid upon expanding in said chamber in response to said predetermined temperature being constricted by said choke portion to multiply its linear expansion for sliding the plunger in said bore throughout said prescribed distance to shift said elements away from one another.

6. An ice motor for a freezing device of the character including a tray and a grid therein having a plurality of relatively movable partitions dividing the interior of the tray into compartments in which water is to be frozen into separated ice blocks, said motor comprising reaction elements forced to move relative to one another at a predetermined temperature below the temperature at which water in the device freezes for reacting between partitions of the grid to move them, one of said

reaction elements having a bore in an end thereof and a chamber opposite to and communicating with said bore, said chamber being substantially larger than the diameter of said bore and having a choke portion tapered toward same, a plunger on the other of said reaction elements slidably mounted in said bore, said plunger being beyond said chamber with its end normally disposed adjacent said choke portion thereof and closing the chamber, said chamber containing a freezable liquid, said freezable liquid expanding in said chamber at said predetermined temperature and being constricted by said chamber choke portion whereby expansion thereof against said plunger multiplies sliding of the plunger in said bore to shift said elements away from one another, a resilient sleeve interposed between said elements sealing the freezable liquid in said motor, and means mechanically clamping an end of said sleeve to said one element and its opposite end to said other element for movement therewith to stretch and tension the sleeve whereby said end of said plunger is returned to its normal position adjacent said choke portion of said chamber in response to thawing of the freezable liquid.
